Archibald Cox

UNITED STATES PATENT OFFICE

JOSEPH AVRUTIK, OF BRONX, NEW YORK

TABLE

Application filed June 21, 1927. Serial No. 200,322.

The invention relates to an improvement in tables, and more particularly to an improvement in auxiliary tables adapted for kitchen, restaurant, tea room, and the like service.

5 One object of the invention is to produce an improved article of furniture consisting of a regulation size table and an auxiliary table of such size and arrangement that it may be used for all the purposes of standard table, and of such relation with the main table that when it is not in use it may be folded up under the main table without interfering with any of the uses to which the main table is put.

10 Another object of the invention is to improve upon the construction and arrangement of the parts of an auxiliary table combined with a main table so as to adapt the auxiliary table for use by children of various ages. To this end the auxiliary table has provision for adjustment not only as to its own height but also as to its relation to the main table and to chairs of regulation height. The improved table embodying these features of invention

15 is more fully described hereinafter and is particularly pointed out in the appended claims.

In the accompanying drawings illustrating the preferred form of invention, Fig. 1 is a perspective view of the improved table, showing the main table in normal position, and the auxiliary table swung out into operative position; Fig. 2 is an end elevation, partly in section, of the main table, with the auxiliary table swung into inoperative position under the main table; Fig. 3 is an enlarged detail side elevation of the upper end of one of the legs and of the adjacent part of the top of the auxiliary table; and Fig. 4 is a view taken 40 along the line 4—4 of Fig. 3.

The improved article of furniture of the present invention is particularly adapted for use in small rooms where the saving of space is a prime essential. The kitchens of modern apartments in large cities are notoriously small and can not accommodate even a family of four who desire to use the room for the double purpose of kitchen and dining room. The table is also adapted for use in restaurants, tea rooms, and the like where it is de-

sired to have the children accompany their parents or friends at the same table without the discomfort imposed on children by eating at relatively high tables while sitting on—for them—relatively low chairs. Although the improved table of the present invention is equally well adapted for any of these various uses, it will be described with particular reference to its use as an article of furniture in the small kitchen of a modern apartment.

The main table of the combination may be of any usual or preferred construction and in the drawings is shown what is known as a porcelain top table comprising the top piece 5 provided on its under side with the depending side and front flanges 6 and 7, the whole being supported by the front legs 8 and rear legs 9. In the front depending flap or flange 7 is fitted a drawer 10. The auxiliary table 70 comprises a top 12 connected at its rear edge with the front flange 7 of the main table by the hinges 13 and supported at its front edge by the legs 14. The lower portions 15 of the hinges 13 are fastened to the under side of the rear edge of the auxiliary table top 12 and near the outer ends thereof. The upper portions 16 of the hinges 13 are elongated and provided with a longitudinally extending slot 17 through which passes a bolt 18. The front faces of the upper part 16 of the hinges 13 are adapted to lie against the rear side of the front flange 7 of the main table and are secured to the flange 7 by the butterfly nuts 19 threaded onto the inner ends of the bolts 18.

The legs 14 which support the front edge of the auxiliary table are slidably received at their upper ends in the sleeves 20 pivoted by means of the hinges 21 to the under side of the front of each lateral edge of the top 12 of the auxiliary table so that the legs 14 and the sleeves 20 may be folded longitudinally under the front edge of the auxiliary table top 12, as indicated at 22 in Fig. 2. To permit the legs to lie adjacent each other 90 against the under side of the front edge of the top 12, the hinges 21 are offset slightly, relatively to each other. When the auxiliary table is in use with the legs 14 swung into upright position, as shown in Fig. 1, the legs 100

14 are held in this position by means of the slotted brackets 24 pivoted at their upper ends 25 to the front edge of the table top 12 and secured at their lower ends by means of the butterfly nuts 26 to the lower part of the front side of the sleeves 20.

To provide for the vertical adjustment of the top 12 of the auxiliary table to accommodate it to the children at the various stages 10 of their growth, or to adapt it for any other purpose, as for supporting a typewriter, sewing machine, or the like where a certain height is essential to perform the work in question, the upper end of each leg 14 is drilled transversely at the points 27 to receive a bolt 28 which passes through a hole in the lower part of the front side of each sleeve 20 and carries on its front end one of the butterfly nuts 26 and on its rear end a nut 29 which 20 bears against the rear side of the upper end of the leg 14. The nut 29 is received in a hole 30 in the rear side of each sleeve 20. By unscrewing the butterfly nuts 26 the bolts 28 may be removed from the holes 27 which they occupy and the legs 14 moved axially in the sleeves 20 to bring the table top 12 to the desired position, whereupon the bolts 28 will be inserted into the new holes 27 in alignment with the holes 31 in the lower 25 edges of the front sides of the sleeves 20. In adjusting the height of the table top 12 by moving the legs 14 in the sleeves 20 the butterfly nuts 19 will also be loosened and the rear edge of the table top 12 moved up 30 or down as desired to bring the table top 12 into a horizontal plane and then the butterfly nuts 19 will be again tightened.

After use the auxiliary table may be folded away under the main table without interfering with the ordinary uses of the latter. The butterfly nuts 26 are loosened and the legs 14 swung towards each other, up under the front edge of the auxiliary table top 12. To avoid accidental displacement 45 from this position the legs 14 may be secured by retightening the nuts 26, the slots 32 in the brackets 24 permitting the front ends of the bolts 28 to slide to the upper ends of the brackets. This action will cause the brackets 50 24 to lie along the front edge of the auxiliary table top 12 when the latter is swung up into inoperative position under the main table. The auxiliary table is held in its inoperative position under the main table by means of a hook 35 pivoted at 36 on the under edge of the rear part of one of the rails on which the drawer 10 slides. A spring 37 acting against the tail 38 of the hook holds the hook 55 in position to engage with the upper side of the front edge of the table 12. The hook 35 may be disengaged from the table top 12 to permit the auxiliary table to be brought into use by pressing rearwardly on the handle part 39 of the hook.

Having thus described the invention what I claim as new is:

1. An article of furniture comprising, a main table including a front depending flange, and an auxiliary table consisting of a top, hinges connecting the rear edge of the top with the front flange of the main table, two legs pivotally connected with the front edge of the top and arranged to swing towards each other up under the front edge of the top, and means on the main table for holding the auxiliary table under the main table when the legs of the auxiliary table have been folded into inoperative position and the top has been swung rearwardly under the main table. 70

2. An article of furniture comprising, a main table including a front depending flange, and an auxiliary table consisting of a top, a plurality of hinges, each hinge consisting of two parts one of which is adapted to be secured under the rear edge of the top and the other part of which is provided with a slot and is adapted to lie against the rear surface of the front flange of the main table, means passing through the slots in the hinges for securing the hinges to the flange, legs pivotally and adjustably secured to the front edge of the auxiliary table top, and means for holding the legs in adjusted position, and means on the main table for holding the front edge of the auxiliary table under the rear edge of the main table when the legs of the auxiliary table have been folded and the top of the auxiliary table has been swung under the main table. 75

3. An article of furniture comprising, a main table, and an auxiliary table consisting of a top adjustably hinged at its rear edge to the main table, a pair of vertically arranged sleeves hinged to the under surface of the front edge of the top so as to swing towards each other under the front edge of the top, a leg the upper end of which is slidably received in each sleeve, means for securing the legs in adjusted position in the sleeves, means for securing the sleeves in fixed relation with the top, and means connected with the main table for engaging the front edge of the top of the auxiliary table for holding the latter under the main table. 90

4. An article of furniture comprising, a main table having a depending flange, and an auxiliary table consisting of a top, a plurality of hinges, one end of each hinge being secured to the under side of the rear edge of the top and the other end of each hinge being slotted and adapted to rest in upright position against the flange, means passing through the slots for securing the slotted part of the hinges to the flange, a pair of sleeves pivoted to the under surface of the front edge of the table top and arranged to swing towards each other and lie against the under surface of the table top, a leg slidably received at its 105 110 115 120 125 130

upper end in each sleeve, the upper end of each leg being provided with a hole, slotted brackets pivotally connected at one end with the table top, a bolt adapted to pass through a hole in the upper end of each leg and through the slot in the adjacent bracket to hold the leg in adjusted position and the sleeve in operative position, and means on the main table for holding the auxiliary table under the main table when the parts of the auxiliary table have been folded and the auxiliary table top swung under the main table.

5. An article of furniture comprising, a main table, and an auxiliary table consisting of a top one edge of which is hinged to the main table and is adjustable vertically thereto, legs for supporting the opposite edge of the auxiliary table top, said legs being hinged 10 to the table top and adjustable vertically thereto, means for holding the legs of the auxiliary table in adjusted and in operative upright position, and means on the main table for holding the auxiliary table top 15 under the main table when the legs of the auxiliary table have been folded upon the under surface of the top thereof and the top has been swung under the main table.
